UNITED STATES PATENT OFFICE.

WILLIAM H. APPLEBY, OF WINDSOR, ONTARIO, CANADA.

DOOR-LATCH DEVICE.

1,427,252.

Specification of Letters Patent. Patented Aug. 29, 1922.

Application filed January 19, 1920. Serial No. 352,520.

To all whom it may concern:

Be it known that I, WILLIAM H. APPLEBY, a subject of the King of England, residing at Windsor, in the county of Essex and 5 Province of Ontario, Canada, have invented certain new and useful Improvements in Door-Latch Devices, of which the following is a specification, reference being had therein to the accompanying drawings.

10 My invention aims to provide a lock or latch device that may be advantageously used in connection with the door of an automobile or other vehicle, the latch device having provision so that it may be operated 15 from the upper edge of a door or at either side thereof, and the device is particularly characterized by the few parts or simplicity of construction entering into the latch device.

20 It is in this connection, that the lock or latch casing is made of a single piece of material cut and bent to provide an enclosure having a latch guide and spring housing, and in the simple form of my invention

25 there is only a pivoted lever besides the latch, spring and casing. With these few parts the lock or latch device can be easily and quickly assembled and as readily installed, while in other forms of my invention handles or knobs are provided so that 30 the lock or latch device may be operated from either side of a door or other closure member.

35 My invention in its various forms will be hereinafter considered and then claimed, and reference will now be had to the drawings, wherein

40 Figure 1 is a side elevation of the lock or latch device, partly broken away and partly in section;

Fig. 2 is a horizontal sectional view of the same in connection with a door jamb and door frame;

45 Fig. 3 is a vertical cross sectional view of the lock casing;

Fig. 4 is a perspective view of the same;

Fig. 5 is a perspective view of a detached latch;

50 Fig. 6 is a vertical cross sectional view of a lock or latch device provided with an outside or single handle;

Fig. 7 is a side elevation of the same;

Fig. 8 is a vertical cross sectional view of the lock or latch device showing the same equipped with two handles, and 55

Fig. 9 is a plan or developed view of a casing blank.

As set forth in the beginning, the latch or lock casing is made from a single piece of material as sheet metal, cut or stamped 60 to provide a blank substantially as shown in Fig. 9 and the blank is substantially rectangular in plan with two side extensions. The greater part of the blank provides a side wall 1 having openings 2 adapted to receive screws or other fastening means so that the side wall of the casing may be connected to a door frame 3 recess 4 or cutaway portion of said frame. One of the extensions of the blank is at a side edge of the 70 wall 1 and when bent on the dash lines 5 at a right angle to the wall 1 said extension provides an end wall 6 having openings 7 for screws or other fastening means employed for connecting the end wall to the 75 edge of the door frame 3.

Another portion of the blank 1 is adapted to be bent on the parallel dash lines 11 to provide walls 8, 9 and 10 adapted to cooperate with the side wall 1 in providing a 80 latch guide and spring housing. The walls 1, 8, 9 and 10 provide a latch guide and spring housing approximately the same length as the side wall 1 and rectangular in cross section, said guide and housing being 85 formed at the upper edge of the side wall 1 and adapted to fit in a groove 14 provided therefor in the door frame 3.

The walls 8 and 9 have lugs 13 at one end thereof adapted to be bent on the dash lines 90 12 at a right angle to said wall and thus form an end abutment or end wall for one end of a coiled spring 15.

At the opposite end of the spring housing the wall 8 has an apertured lug 16 that is 95 bent upwardly on the dash line 17 at right angles to said wall, so that it may cooperate with the end wall 6 in holding the casing relative to the door frame 3.

Slidable within the guide and spring 100 housing is a latch 18 that is rectangular in cross section and prevented from turning by the walls of the housing. The outer end of the latch is beveled as at 19, and adapted to

snap into engagement and behind a keeper 20 carried by the door jamb 21. The inner end of the latch 18 is tapered or conical, as at 22, and extends into the outer convolutions of the spring 15 so that it may place the spring under compression when the latch is retracted.

Pivottally connected to the side wall 1, adjacent the lower edge thereof, by a rivet 23 or other pivotal means, is the lower end of an operating lever 24, and said lever extends through slots 25 and 26 of the walls 8 and 10 respectively and engages in a notch 27 provided therefor in the side wall of the latch 18. The lever 24 is offset, as best shown in Fig. 1, and the upper end thereof terminates in a handle 28 which protrudes above the door frame convenient for manipulation so that said lever may be oscillated to retract the latch 18 and released to permit of the expansive force of the spring 15 distending the latch for engagement with the door jamb keeper 20. As shown in Figs. 2 and 3 the lever 24 extends upwardly at the inner side of the side wall 1 and is held against displacement by the latch and its guide. The lever is normally held against end walls of the slots 25 and 26 by the expansive force of the spring 15, and when closing the door there is sufficient clearance in the notch 27 of the latch to permit of the latch being partially retracted by the keeper 20 before the lever 24 is engaged. This permits of the latch gaining sufficient impetus to shift the lever 24 and permit of the door being completely closed, before the lever assumes a normal vertical position as shown in Fig. 1.

Sometimes it is desirable to use inner and outer handles or knobs for the lock or latch device, and by reference to Figs. 6 and 7, it will be observed that the door frame 3 is provided with a rotatable spindle having a tang 30^a extending into an opening provided therefor in the lower offset end of a lever 31.

The lower end of the lever 32 is slotted and loosely supported by a rivet 31 and this rivet is simply employed to hold the lever against accidental displacement when the spindle 29 is withdrawn. The outer end of the spindle 29 has a conventional form of handle 32 with the base of the handle ro-

tatable in a socket or escutcheon plate 33 on the outer side of the door frame, and a detachable collar 34 on the spindle 29 prevents such spindle and its handle from becoming accidentally displaced relative to the socket plate 33.

When door knobs or handles are to be used, as shown in Fig. 8, it is not necessary to use a long lever for engagement with the latch, but simply a short lever or arm 35. It is also unnecessary to use the collar 34, as a handle or knob 36 may be mounted on the inner end of a spindle 37 which is of greater length than the spindle 29, the spindle and its handles or knobs permitting of the lever or arm 35 being oscillated to retract the latch of the lock.

It is thought that the operation and utility of the latch device will be apparent without further description, and while in the drawings, there are illustrated the preferred embodiments of my invention, it is to be understood that the structural elements are susceptible to such changes as fall within the scope of the appended claim.

What I claim is:—

A door latch device made from a blank cut to provide a side wall, an end wall, a lug, and walls which are bent to form a housing longitudinally of the upper edge of said side wall, said housing walls having bent portions affording an end abutment, said housing walls having lever slots, a lever extending through the lever slots against said side wall, a spring in said housing against the end abutment thereof, a latch slidable in said housing and having a notch through which said lever extends, said latch having a conical end extending into an end of said spring, a handle spindle extending through said side wall and adapted for oscillating said lever to shift said latch in said housing, and a handle on each end of the spindle so that the latch may be operated from either side of the door.

In testimony whereof I affix my signature in the presence of two witnesses.

WILLIAM H. APPLEBY.
